UNITED STATES PATENT OFFICE.

GEORGE H. GILMAN, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

PRESSURE-FLUID-ACTUATED TOOL.

1,171,113.

Specification of Letters Patent.

Patented Feb. 8, 1916.

Application filed April 26, 1912. Serial No. 693,336.

To all whom it may concern:

Be it known that I, GEORGE H. GILMAN, a citizen of the United States, and a resident of Claremont, county of Sullivan, State of New Hampshire, have invented an Improvement in Pressure-Fluid-Actuated Tools, of which the following description, in connection with the accompanying drawings, is a specification, like characters on the drawings representing like parts.

My invention relates to pressure fluid actuated tools, and is more particularly concerned with provision for permitting a turning movement of the cylinder and drill-bit, or other tool, with respect to the grasping handle, while utilizing a longitudinal sliding movement of the latter to control the throttle valve.

My invention will be best understood by reference to the following specification, when taken in connection with the accompanying illustration of one specific embodiment thereof, while its scope will be more particularly pointed out in the appended claims.

In the drawings: Figure 1 is a longitudinal central section of a pressure fluid actuated tool embodying one form of my invention, and Fig. 2 is a detail sectional view on line 2—2 of Fig. 1.

Referring to the drawings, and to the specific embodiment of my invention which I have there disclosed for illustrative purposes, I have there shown a pneumatic tool having a cylinder 3, in which a piston 4 is mounted to reciprocate in the usual well-known manner, and any usual or desired tool, as for example a drill-bit 5, may be and preferably is mounted in a tool sleeve or bushing 6 in the front end of the cylinder 3. Herein the tool is of the percussive or hammer type, and the piston 4 is provided with an extension 7 adapted to strike the inner end of the drill-bit 5 in the usual and well-known manner. The piston may be controlled in its movements in any usual or desired manner, which it will be unnecessary to describe herein, since it is not essential to the illustration of my present invention. The cylinder 3 may be and preferably is provided at its rear end with a hollow casing 8, having a pressure fluid supply passage 9 communicating with a constant pressure

chamber 10. The supply passage 9 may be and preferably is controlled by any suitable type of throttle valve 11, extending longitudinally of the tool and across the supply passage 9. The throttle valve which I have chosen to employ in connection with my present invention is provided with piston heads 12 and 13, separated by a reduced portion 14. The piston head 12 works in a cylindrical chamber 15 suitably formed in the casing 8, to the bottom of which chamber a pressure duct 16 leads through the supply passage 9, the lower end of the piston head 12 being thereby exposed to constantly acting pressure fluid.

The throttle valve 11 is under control of a grasping handle 17, which is mounted to slide longitudinally and swivel with respect to the cylinder 3. Preferably the grasping handle 17 is mounted to swivel upon a longitudinally slidable head 18, which bears against the rear end of the throttle valve 11, and has a limited longitudinal sliding movement with respect to the cylinder, its movement being limited by suitable means, as for example, a stud 19 projecting through a slot 20 provided in the slidable head and screwed into the hollow casing 8. This stud may also serve as a conduit for the pressure fluid supply, and to that end it is herein provided with an air inlet passage 21 communicating with the supply passage 9.

When the tool is pressed against its work, the hand pressure upon the grasping handle 17 acts against the head 13 of the throttle valve 11, and forces the latter into the position shown with its reduced portion 14 lying across the supply passage 9 and permitting free passage therethrough of the pressure fluid. When the operator withdraws the tool from the work and relieves the pressure of his hand against the grasping handle, the constantly acting pressure fluid upon the piston head 12 at the forward end of the throttle valve forces the latter back against the sliding head 18, and pushes the latter rearwardly upon the casing 8. The valve follows the slidable head in its movement until the latter is brought to rest against the stud 19, this movement of the valve being sufficient to bring the throttle valve's piston head 12 across the supply passage 9 into position to close the same.

The grasping handle 17 may be swiveled upon the slidable head 18 in any suitable manner, as for example, by providing the head with a reduced portion 22 receiving an internal annular flange 23 within the bore of the handle 17, and by providing a nut 24 having screw-threaded engagement with the sliding head and acting to prevent the grasping handle from being pulled off of the latter. This nut may be prevented from unscrewing by suitable means, as for example, a split spring washer 25 bearing thereagainst and encircling the reduced portion 22 of the head 18.

15 The pressure fluid is herein supplied to the tool through a conduit 26 having a passage 27, communicating with the passage 21 and the usual hose (not shown) may be coupled on to this fitting in any usual or desired manner. The conduit 26 may if desired, without further provision, constitute a grasping handle for turning the cylinder with respect to the grasping handle 17, but I prefer to provide the conduit 26 with a 25 laterally extending grasping handle 28 for this purpose. The operator grasps the grasping handle 17 with one hand, and the grasping handle 28 with the other hand, and while pressing the tool against the work 30 turns the same to and fro with respect to the handle 17, by swinging the handle 28 to and fro. By this means, the cylinder, acting through the bushing 6, turns the drill-bit 5 to and fro as the drilling operation proceeds.

35 While I have herein shown and described one specific embodiment of my invention for illustrative purposes, and have disclosed and discussed in detail the construction and arrangement incidental to one specific embodiment thereof, it is to be understood that the invention is limited neither to the mere details or relative arrangement of parts, nor to its specific embodiment herein shown, but 40 that extensive deviations from the illustrated form or embodiment of the invention may be made within the scope of the claims without departing from the principles 45 thereof.

Having thus described one embodiment of my invention, what I claim is:

1. In a pressure-fluid actuated tool, the combination with the cylinder and piston, of a grasping handle mounted to slide longitudinally and swivel with respect to said cylinder, a longitudinally slidable throttle valve under the control of said handle, a laterally extending grasping handle for turning said cylinder with respect to the first-mentioned grasping handle, the second mentioned handle being provided with a pressure-fluid supply passage.

2. In a pressure-fluid actuated tool, the combination with the cylinder and piston, of a head mounted to slide longitudinally with respect to said cylinder, a grasping handle swiveled upon said head, a longitudinally slidable throttle valve under the control of said sliding head, laterally extending means to conduct pressure-fluid toward said throttle valve, and a laterally extending grasping handle for turning said cylinder with respect to first-mentioned grasping handle, the second mentioned grasping handle being provided with a pressure-fluid supply passage leading toward said throttle valve.

3. In a pressure-fluid actuated tool, the combination with the cylinder and piston of a head mounted on said cylinder and provided with a reduced portion, a grasping handle swiveled on said head, means for holding said grasping handle in place on said head comprising a member secured to said reduced portion, said handle being provided with an inwardly projecting portion 35 interposed between said member and said head, and retaining means for said member interposed between said reduced portion and said inwardly projecting portion and between said member and said head.

In testimony whereof, I have signed my name to this specification in the presence of two subscribing witnesses.

GEORGE H. GILMAN.
